UNITED STATES PATENT OFFICE.

CHARLEY HENRY HEIDER, OF GLENMORA, LOUISIANA.

LUMBER-STAMPING DEVICE.

1,258,215.

Specification of Letters Patent. Patented Mar. 5, 1918.

Application filed April 30, 1917. Serial No. 165,553.

To all whom it may concern:

Be it known that I, CHARLEY H. HEIDER, a citizen of the United States, residing at Glenmora, in the parish of Rapides and State of Louisiana, have invented a new and useful Lumber-Stamping Device, of which the following is a specification.

The present invention appertains generally to printing and stamping devices, and relates more particularly to an appliance for stamping or imprinting characters in lumber, or the like.

The object of the invention is to provide a novel and improved device for stamping lumber for purpose of identification, record, advertisement, or the like, and such data as the name and address, date, grader's number, planing machine number, trade mark, advertisement, etc., can be imprinted or stamped in the lumber as it comes from the planing machine, thus rendering the device automatic in operation, and the lumber in being marked or stamped will serve as an identification in case of dispute or lost shipment.

The present device is designed for attachment to a planing machine, or the like, to operate automatically for printing or stamping the desired characters in the lumber as it leaves the planing machine, the device being comparatively simple and inexpensive in construction, readily applied and practical and effective in operation.

Another object of the invention is to provide a device of that character of such construction that the dies will not clog or choke up with gum, pitch, rosin or other accumulations, as when stamping pine or similar lumber, thus avoiding the blurring of the characters which would result if the dies became clogged.

A still further object of the invention is to construct a machine of the nature indicated which is adjustable for various thicknesses of lumber, and which is adjustable to either stamp the upper or the lower surface of the lumber, and which can also be positioned to stamp either edge of the lumber as it comes from the planing machine.

With the foregoing and other objects in view which will appear as the description proceeds, the invention resides in the combination and arrangement of parts and in the details of construction hereinafter described and claimed, it being understood that changes in the precise embodiment of

the invention herein disclosed, can be made within the scope of what is claimed, without departing from the spirit of the invention.

The invention is illustrated in the accompanying drawing, wherein:—

Figure 1 is a side elevation of the device showing the same in position for stamping the upper surface of the lumber.

Fig. 2 is an opposite side elevation showing the parts adjusted for stamping the lower surface of the lumber, portions being shown in section.

Fig. 3 is a sectional detail on the line 3—3 of Fig. 2, with the pressure roller or wheel removed.

Fig. 4 is a section on the line 4—4 of Fig. 2.

Fig. 5 is a fragmental elevation on an enlarged scale illustrating the dies in the rim of the stamping wheel.

Fig. 6 is a sectional perspective view of one of the dies.

In carrying out the invention, there is provided a suitable bracket 1, which as illustrated embodies the supporting or attaching plate 2, a shelf or plate 3 at right angles with the plate 2, and brace flanges or ribs 4 between said plates 2 and 3. The plate 2 is elongated and is provided near its ends with elongated slots 4' for the reception of clamping bolts 5 to clamp the plate 2 against the rear end of the bed 6 of a planing machine or the like, so that the lumber will pass over or across the shelf or plate 3. The plate 3 has a slot 7 between two of the flanges 4, and the bracket has a clamp 8 united with another flange 4 and the plate 3, said clamp being provided with a clamping bolt 9, and a spindle or standard 10 extends through the clamp 8, and is in a vertical position as illustrated. The spindle 10 extends above and below the clamp 8, and can be readily set to the desired position by loosening the bolt 9. The bracket 1 thus carries the spindle 10, which spindle in turn carries the stamping or operating part of the invention.

A split clamping sleeve 11 embraces the spindle 10 below the split clamp 8, and has a clamping bolt 12 for contracting it tightly upon the spindle to hold the sleeve 11 in any adjusted position. A split sleeve 13 is slideable upon the spindle 10 above the clamp 8 and bracket 1, and is provided with a clamping bolt 14 whereby said sleeve can be contracted to take up wear, and also to

tightly embrace the spindle 10, when desired, for holding the sleeve 13 in fixed position. The upper sleeve 13 has a feather 15 to work within a longitudinal featherway 16 with which the spindle 10 is provided, whereby to prevent the rotation of the sleeve 13, but to permit the sleeve to reciprocate or slide longitudinally of the spindle. The sleeves 11 and 13 each have a pintle 17 extending to one side therefrom in the same direction from the spindle 10, and a bolt 18 or other retaining element is engageable upon the free end of the pintle 17. These pintles are adapted for the removable and interchangeable engagement therewith of a pressure roller or wheel 19 and a stamping or printing wheel 20. As shown in Fig. 1, the wheels 19 and 20 are applied to the respective sleeves 11 and 13, while as shown in Fig. 2, the wheels are reversed, it being evident that the wheels can be readily applied interchangeably with the pintles 17 of said sleeves, to rotate thereon.

The rim 21 of the wheel 20 is provided with an annular slot 22 dividing said rim into two annular side sections which are spaced apart, and the two sections of the rim are provided at their inner faces and adjacent to their outer edges with confronting or complementary undercut grooves 23 jointly providing a dovetailed or undercut slot in the periphery of the wheel 20. This dovetailed slot is adapted to hold any suitable number of dies 24 which are dovetailed 35 to fit the grooves 23. The dies may have any suitable letters, numerals or characters, and can be used interchangeably to provide the desired wording or mark, according to the circumstances, the faces of the dies projecting from the periphery of the wheel 20 to press into the lumber. It will be noted in this connection that the rim of the wheel 20 works within the slot 7 between the respective flanges 4, and that the dies project beyond 40 the plane of the face of the plate 3 when the wheel 20 is applied to the sleeve 11 with said sleeve properly adjusted with respect to the bracket 1. At each end of the set or series of dies 24, there is a step block or blank die 25, which serves to prevent the end dies from entering too deep into the lumber, as 45 the end dies engage and leave the lumber, respectively.

Importance is attached to the fact that each die 24 is provided with an opening or hole 26 extending from its face to its base and communicating with the slot 22, whereby gum, pitch, rosin, sawdust or other accumulations which enter the characters of the dies will be forced by pressure against the lumber into and through the openings or holes 26, thereby preventing the characters of the dies from being clogged or choked, as would result in the blurring of the marks 55 on the lumber. The accumulations which

pass through the openings 26 will readily pass or fall through the slot 22.

The side sections of the rim 21 are connected by screws 27 or other clamping elements whereby to clamp the dies between the sections of the rim, and to hold said rim sections in place, it being noted that the dies 24 seat against the shoulders formed by the grooves 23 to prevent the dies from being pressed toward the center of the wheel 20. When the screws 27 are loosened, the rim sections can be separated for purpose of inserting and removing the dies, and to facilitate this, one of the spokes of the wheel 20 is slit, as at 28, inwardly from the slot 22, to enable the rim sections to be spread sufficiently at this point for removing and inserting the dies. Said dies can be slid longitudinally to and from the slit spoke. Due to the dovetailing of the dies and the slot in which they are seated, the dies will not drop out even though the screws 27 become loosened, and the dies will be held in place between the blocks 25.

A coiled wire expansion spring 29 surrounds the spindle 10 and is confined between the sleeve 13 and a nut 30 or equivalent member threadedly or otherwise adjustably engaged upon the upper terminal of the spindle 10. The movement of the sleeve 13 under the tension of the spring is limited by means of an adjustable collar or stop 31 mounted upon the spindle 10 and held in any adjusted position by means of a set screw 32 or its equivalent.

With the parts in position as illustrated in Fig. 1, the stamping wheel will be above the lumber and in being carried by the sleeve 13 will be pressed downwardly against the lumber under the influence of the spring 29, the nut 30 being readily adjusted to regulate the tension of the spring for forcing the sharp edges of the dies into the lumber. By thus regulating the tension of the spring 29, this will regulate the depth to which the edges of the dies are forced into the lumber, and furthermore, the collar or stop 31 can be adjusted to limit the movement of the stamping wheel toward the lumber, thereby regulating the depth of the mark in the lumber. Since the stamping wheel is yieldably depressed, it can yield should the dies engage knots or other hard unyielding portions, thus avoiding the flattening or injuring of the dies. In this position of the parts, the pressure wheel or roller 19 is idle, and can be carried by the lower sleeve 11 so as to be out of the way.

With the parts arranged as seen in Fig. 2, the stamping wheel 20 is below the lumber, being carried by the sleeve 11, and said sleeve can be adjusted to regulate the amount that the dies project above the surface of the plate 3 over which the lumber moves. This serves to regulate the depth to

which the dies are forced into the lower surface of the lumber, and this can also be adjusted by regulating the tension of the spring 29 by the adjustment of the nut 30, thus increasing or decreasing the pressure of the wheel or roller 19 against the lumber. The wheel 19 presses the lumber downwardly against the rim of the wheel 20 and dies, and the collar 31 can be adjusted to limit the downward movement of the sleeve 13 and wheel 19, thereby limiting the amount that the lumber is pressed downwardly against the dies, to avoid the excessive depth of the mark in the lumber.

15 By changing the position of the bracket 1 to bring the spindle 10 horizontal, the device can be used for stamping or imprinting the mark in either edge of the lumber, it being noted that both the stamping and pressure wheels can be adjusted relatively for various thicknesses and widths of lumber. Thus, by separating said wheels, lumber of greater thickness or greater width can be accommodated.

20 25 The dies are made from the best grade of tool steel and are tempered very hard so as to eliminate wear, and as above explained, are constructed so as to clean themselves automatically to avoid clogging thereof, which is especially important when stamping such lumber as pine, containing gum, pitch, turpentine, rosin or the like.

Having thus described the invention, what is claimed as new is:—

30 35 1. A device of the character described embodying a wheel having a rim provided with a slot dividing the rim into resilient side sections, marking elements fitted between said side sections of the rim, and means for clamping said side sections of the rim toward one another to clamp said elements therebetween.

40 45 2. A lumber stamping device embodying a wheel having a rim provided with a slot dividing said rim into resilient side sections, dies held between said sections and having openings extending from their faces and communicating with said slot for the outlet of accumulations.

50 55 3. A device of the character described embodying a wheel having a rim provided with a slot dividing the rim into resilient side sections, said sections having complementary grooves in their adjacent sides, marking elements seated in said grooves and projecting from said rim, and means engaging said side sections for clamping said elements therebetween.

60 4. A lumber stamping device embodying a wheel having a rim provided with a slot dividing the rim into resilient side sections,

said sections having undercut grooves in their adjacent sides, dies seated in said grooves and having faces projecting from said rim, and openings extending from said faces and communicating with said slot for the outlet of accumulations, and means engaging said sections for clamping dies therebetween.

5 5 5. A lumber stamping device embodying a wheel, a set of dies upon the periphery thereof, and step portions at the ends of said dies to prevent the excessive movement of the end dies into the lumber.

10 15 6. A lumber stamping device embodying a bracket having a clamp, a spindle held by said clamp, an adjustable member carried by the spindle, and a stamping wheel carried by said member having a lumber engaging die.

20 25 7. A lumber stamping device embodying a bracket having a clamp, a spindle held by said clamp, an adjustable member carried by the spindle, a stamping wheel carried by said member having a lumber engaging die, and means upon said spindle for pressing the lumber and wheel together.

30 35 8. A lumber stamping device embodying a spindle, a pair of sleeves mounted thereon, a stamping wheel and pressure wheel interchangeably applicable to said sleeves to be carried for rotation thereby, spring means for moving one sleeve toward the other, and means for limiting the movement of the spring pressed sleeve.

40 45 9. A lumber stamping device embodying a bracket, a spindle held by said bracket, sleeves upon said spindle at opposite portions of said bracket, a stamping wheel, a pressure wheel, said sleeves having means for interchangeably supporting wheels for rotation, spring means for pressing one of the sleeves toward the bracket, and adjustable means for limiting the movement of said sleeve toward the bracket.

50 55 10. A lumber stamping device embodying a bracket, a spindle carried by the bracket, a sleeve slidable upon the spindle and having an outstanding pintle, a lumber engaging wheel rotatable upon said pintle, spring means between said sleeve and pintle for moving the wheel against the lumber, and adjustable means for limiting the movement of the sleeve on the spindle.

60 65 In testimony that I claim the foregoing as my own, I have hereto affixed my signature in the presence of two witnesses.
